Primary Examiner — Selina Sikder(74) *Attorney, Agent, or Firm* — Casimir Jones, S.C.(57) **CLAIM**

The ornamental design for a control panel, as shown and described.

DESCRIPTION

FIG. 1 is a front perspective view showing my new design; FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The broken lines in the drawings depict unclaimed environmental subject matter.
